UNITED STATES PATENT OFFICE.

JOHN JACOB SCHAIRER, OF CLINT, TEXAS, ASSIGNOR OF FORTY-NINE ONE-HUNDREDTHS TO F. E. HUNTER, OF EL PASO COUNTY, TEXAS.

FRUIT-JAR AND CAN OPENER.

SPECIFICATION forming part of Letters Patent No. 606,587, dated June 28, 1898.

Application filed November 9, 1897. Serial No. 657,990. (No model.)

To all whom it may concern:

Be it known that I, JOHN JACOB SCHAIRER, of the town of Clint, in the county of El Paso and State of Texas, have invented a new and Improved Fruit-Jar and Can Opener, of which the following is a full, clear, and exact description.

My invention relates to improvements in devices for turning the screw caps or covers of fruit-jars, cans, and similar vessels which require to be screwed up tightly when the vessel has been filled and is to be set aside and which become more or less set and require considerable force in unscrewing when the vessel is to be opened.

My invention has for its object to provide a cheap, simple, and yet effective instrument for the purpose above referred to; and it consists in the novel device hereinafter described and claimed.

Reference is had to the accompanying drawings, wherein the same parts are indicated by the same letters throughout the several views.

Figure 1 represents a perspective view of a strip of metal or "blank" such as is used in making my improved device. Fig. 2 represents an edge side elevation of the strip or blank after its central portion has been twisted in the process of forming the device, and Fig. 3 represents a side elevation of the finished device ready for use.

The strip of metal or blank A A is of a sufficient length to partially encircle the periphery of the screw-cap upon which it is to be used and to allow for two end pieces of sufficient length to be grasped together by the hand of a person when the device is in use. This metal strip or blank should have a greater width than thickness, so that it may be readily bent, and yet its thickness should be great enough to give to it the necessary degree of strength and rigidity, although the metal of which the said strip or blank is composed should be of such a quality as to allow some degree of flexibility thereto when in use. The longitudinal edges of the said strip or blank should be square or sharp, so as to form effective gripping-surfaces, as hereinafter described.

In forming the device the blank A A is first 50 twisted along its central or intermediate portion B B into the form of a spiral, as seen in Fig. 2, the convolutions of which spiral should not be very close, so that the corners b b of the edge of the blank may present themselves 55 prominently, as also seen in Fig. 2. After being thus twisted the strip A A is bent along the said twisted portion into the form of a horseshoe, as seen in Fig. 3, so as to partially encircle the periphery of the cap to which it 60 is to be applied, the untwisted ends of the said strip or blank being preferably left straight to serve as hand-grips in manipulating the device, as also shown in Fig. 3. These untwisted end portions of the strip or blank 65 may be left plain and straight and fitted with wooden or other suitable handles or may be used without such handles, in which latter case the edges would be rounded, and the said end portions might be curved in any 70 manner to render them more easily held by the hand; but the exact manner of finishing off the end portions of the strip or blank is immaterial; as this may vary to suit requirements without affecting the nature or scope 75 of my invention.

Having thus described my invention, what I claim, and desire to secure by Letters Patent of the United States, is—

1. A spring-metal wrench made from a strip 80 or "blank" of metal having sharp corners upon its longitudinal edges, the said blank being twisted into the form of a spiral along its central portion, and having said twisted portion bent into the form of an arc of a circle, substantially as described.

2. A spring-metal wrench made from a strip 85 or "blank" of metal of greater width than thickness having sharp corners upon its longitudinal edges, the said blank being twisted 90 into the form of a spiral along its central portion, and having said twisted portion bent in the direction of its thickness into the form of an arc of a circle, substantially as described.

JOHN JACOB SCHAIRER.
